UNITED STATES PATENT OFFICE.

OTTO PETERMANN, OF GROTON, NEW YORK, ASSIGNOR TO CORONA TYPEWRITER COMPANY, INC., A CORPORATION OF NEW YORK.

TYPE-WRITING MACHINE.

1,203,255.

Specification of Letters Patent.

Patented Oct. 31, 1916.

Application filed January 30, 1915. Serial No. 5,240.

To all whom it may concern:

Be it known that I, OTTO PETERMANN, a citizen of the Republic of Switzerland, and a resident of Groton, county of Tompkins, and 5 State of New York, have invented certain new and useful Improvements in Type-Writing Machines, of which the following is a full, clear, and exact description.

This invention relates more particularly 10 to silent or dead key actions for typewriting machines for printing accents or for under-scoring purposes.

One of the principal objects of the invention is to provide simple means whereby one 15 or more of a series of keys may be converted into a dead, silent or accent key, and the said key made to operate a ribbon vibrator to move the ribbon to and from the printing point a distance corresponding to that obtained by the ordinary key and at the same 20 time prevent the tripping of the escapement so that the carriage will not be moved by its letter-spacing mechanism.

Another object of the invention is to provide a simple and efficient attachment which 25 may be arranged to form a stop or bumper effect for each key-operated lever.

Other objects of the invention are to provide simple and efficient means whereby very 30 little change is required in typewriting machines of the visible, portable type to adapt any one of the keys to be made a dead or silent key; and to provide simple and efficient means whereby a single rocking frame may 35 be operated by all of the key-levers and with some of the key-levers given a greater movement than by others to adapt both the escapement and ribbon vibrating mechanisms to be operated by certain of the keys and 40 only the ribbon mechanism to be operated by one or more other keys.

A further object of the invention is to provide simple and efficient means forming a dead key action which is particularly 45 adapted for typewriting machines in which the carriage and the keys are brought into close relation with respect to each other in order that the machine may be made more compact when not in use than when in its 50 normal working position.

A still further object of the invention is to

provide a direct locking connection between one or more key-operated levers and a part of the mechanism controlling the feed of the carriage.

With these and other objects in view, the invention will be hereinafter more particularly described with reference to the accompanying drawings, which form a part of this specification, and will then be pointed out 55 in the claims at the end of the description.

In the drawings, Figure 1 is a fragmentary longitudinal section, partly in elevation, showing one form of machine embodying my invention. Fig. 2 is a fragmentary 65 view showing how the dead or silent key mechanism remains ineffective when the ordinary key is operated so that both the ribbon mechanism and the escapement mechanism are operated. Fig. 3 is a view similar to Fig. 2 70 except that the dead key has been actuated so that only the ribbon mechanism will be moved. Fig. 4 is a detail view of a guide or bracket forming a part of the dead key mechanism. Fig. 5 is a detail perspective 75 view of the dead key lock or locking element. Fig. 6 is a transverse vertical section through the machine, partly broken away and partly in elevation, showing the location of the dead key mechanism and the 80 parts with which it cooperates. Fig. 7 is a detail perspective view of an element adapted to form a stop to positively limit the movement of the dead or silent key; and Fig. 8 is a detail plan view of a part of one 85 form of ribbon vibrating mechanism.

While the invention is shown as applied to a typewriting machine wherein the carriage is mounted upon a foldable support in order that the carriage may be moved 90 forward to substantially overhang the keys, it will be understood that the invention or certain parts thereof may be applied to typewriting machines of various kinds.

The frame 10 of the machine has a rear 95 plate 11 and side plates 12 and may be of any suitable form. A plurality of rods 13 extend transversely of the machine between the sides 12, and mounted to swing on said rods are key-levers 14 and 15. These key-levers are arranged in banks or sets and have the usual key for operating the same.

and form a part of a universal keyboard. There may be one or more key-levers 15, and this lever, while similar to the ordinary key-operated levers 14, is shown as having been converted into what is known as a dead or silent key or key-lever. Each key-lever is normally held in the downward position by a spring 16, one end of which is secured to the key-lever in advance and at the rear of its pivot rod 13 and the other end of said spring is secured to a transversely extending bar or plate 17. At the rear portion of each key-lever is a horizontally extending part 18 from which projects a lug 19. This lug 19 is connected by a link 20 to a type-bar 21 on the outer end of which is a type head 22 having type 23 which are adapted to be forced upwardly and rearward to print against a platen 24. The platen 24 is mounted upon a carriage 25 and this carriage 25 is adapted to move transversely of the machine on a bed 26. The bed 26 is secured to two arms 27 of a foldable support so as to adapt the carriage and platen with the parts mounted on the bed to be folded forward into substantially overhanging relation to the keys as is common in this class of machine. The carriage 25 has a rack 28 which is adapted to be engaged by a loose dog 29 and a fixed dog 30 which are mounted on a dog carrier 31 to move transversely of the rack, the carriage being connected to a tension drum 32 to move the carriage when released by the operation of the dogs in the usual way. The dog carrier has a projecting part 33 which is adapted to be engaged by a tappet 34 forming a part of a rocking frame 35. This frame 35 is substantially U-shaped in form and comprises a horizontally extending bar 36 and vertically arranged arms 37 which are pivotally held to a transverse rod 38. This transverse rod may be guided at its ends in brackets 39 on the rear frame plate 11 and is connected to suitable platen shift mechanism, the arms 40 forming a part of said mechanism only being shown. The arms 40 are held at one end to a rod 41 and their other ends are connected to the transversely extending rod 38, which latter is also secured to vertical posts or slides 42 by which the carriage bed and platen as well as the rocking frame 35 are given a vertical shift movement. The upper ends of the vertical arms 37 of the rocking frame are slotted, as at 43, and extending transversely through said slotted portions is a rod 44. This rod 44 is held in the upper arms 45 of bell-crank levers 46. The bell-crank levers 46 are pivotally held to brackets 47 forming guides for the slides 42, and said bell-crank levers have their other arms pivotally connected, at 48, to the upright portions 49 of a universal bar 50. The universal bar 50 has a horizontally extending portion 51 which extends trans-

versely of the machine over all of the key-levers and adapted to be engaged by a lip or tongue 52 on each key-lever so as to move the universal bar upwardly at each depression of a key. This will cause the bell-crank levers 46 to operate the transverse rod 44 and through said rod impart a rocking motion to the rocking frame, thus during the movement of the ordinary key-levers, the rocking frame may be moved back and forth so as to trip the escapement to permit the carriage to move for letter-spacing under the tension of the spring drum 32.

The transverse bar 36 of the rocking frame 35 has an upwardly projecting portion 53 which is adapted to enter a slot 54, Fig. 8, in a ribbon vibrator actuating member 55 and be separable therefrom when the machine is folded. This actuating member 55 is pivotally held, at 56, to a bracket 57 mounted upon the carriage bed. On the actuating member 55 is an adjustable cam lever 58 which is pivoted, at 59, to the actuating member 55 and has cam sides 60 which are adapted to engage a roller 61 carried by a ribbon vibrator 62, the latter being pivoted, at 63, to an arm of the bracket 57 and having a portion 64 through which the ribbon is threaded. The lever 58 is adjusted and held in different positions to permit a bichrome ribbon to be used, as for example when positioned over the letter B the black field of the ribbon may be used, when over the letter R the red field may be used, and when moved to a position over the letter S, at which time the cam sides 60 are at substantially an arc with the pivot 56 as a center, the ribbon vibrator may remain silent or inactive or substantially so and below the printing point to adapt the machine for making stencils. As the rocking frame is moved back and forth at the depression of each key, the actuating member 55 is also moved back and forth and according to the position of the lever 58, the ribbon vibrator 62 will have its throw varied or permitted to remain inactive. The parts as thus described may be of the usual or of any preferred construction or may be such as disclosed in my pending application, Serial No. 714,842, filed August 13, 1912.

To render one or more of the keys or key-levers silent for printing accents or for underscoring letters which requires that the ribbon vibrator be actuated on the depression of the key without tripping the escapement, I provide a locking element or member 65. This locking element is bar-like in form and has its lower end slotted, at 66, through which passes an extension or tongue 67 at the rear end of the silent key-operated lever 15. The extension 67 of each key-lever whether of the ordinary type or of the dead or silent key type is guided in a slot 68 in a comb plate 69 which extends trans-

- versely of the machine and which serves to guide the inner or rear end 67 of each key-lever, the said comb plate being inclined vertically and rigidly held to the brackets 39 by screws 70 or otherwise. The slots 68 of the comb plate 69 are of sufficient length to permit complete depressions of the ordinary key-levers and are somewhat longer than the slot 66 of the locking element 65 so that on the depression of the silent or dead key-lever 15 and after a certain movement thereof, the said locking element 65 will be moved upwardly, as shown in Fig. 3. The locking element or member 65 has an offset portion 71 and at its upper portion has an angular upper end 72 through which is a slot 73. A bracket or plate 74 which is secured to the rear portion of the machine frame by screws 74^a or otherwise, has a tongue or part 75 which enters the slot 73 and serves as a guide for the upper portion of said locking element. It will be evident that when the dead key is operated as shown in Fig. 3, the upper end of the locking element 65 will be forced into the path of movement of the transversely extending rod 44 and will prevent further movement of said rod. This will prevent further depression of the silent key which actuates the rod 44 through the universal bar and bell-cranks as already described, and as said rod passes through the slotted portions of the rocking arms 37, the frame 35 formed by said arms and transverse bar 36 is positively locked against further movement and at a point which will not trip the escapement. This movement, however, is such that the ribbon carried by the vibrator is moved to cover the printing point and the depression of the silent key is such as will cause the type to be moved near enough to the platen so that the momentum obtained through the depression of the silent key will be sufficient to force the type to make the impression on the work sheet, the frame 35 being restored when the key is released to its normal position by a spring 76 or otherwise as desired.
- A bumper or stop device 77, shown in detail in Fig. 7, is provided to prevent all liability of the dead key being depressed too far and thereby possibly cause "bleeding" when a bichrome ribbon is employed or the liability of the key forcing the rocking frame far enough to trip the escapement.
- This device 77 has a plate-like body 78 having spring clip ends 79 at the lower portion thereof which is adapted to span the lower edge of the comb plate 69 to hold the said device detachably to said comb plate and in such a way as to prevent upward movement thereof. The body 78 has a slot 80 which is adapted to register with the guide slot for the dead key in the comb plate and said slot 80 is of less length than the slot 68 of said comb plate so that the upper edge 81 of said
- slot will serve to engage the projecting lip or part 67 of the key-lever when fully depressed as shown best in Fig. 3. By this means the extent of depression of the dead key is limited so that independent of the locking effect secured by the upper end of the locking element 65 any lost motion which might permit further movement of the rocking frame on the depression of the key is effectually prevented. 75
- The locking element or member 65 may be held in its normal position by a spring 82. This will prevent the element 65 from falling or moving out of position when the machine is turned upside down or otherwise handled during transportation. This spring may have one end fastened to a tongue 83 pressed from the body of the locking element 65 and the other end may be held to an extended end of the lower fastening screw 74^a of the bracket 74. The inner end of the lower screw 74^a is extended inward, as at 84, and passes through a slot 85 in said locking element 65, said end of the screw acting as a guide for the bar or locking element 65 as well as means to which one end of the spring 82 may be attached. 80
- It will be seen that the parts are constructed so that the dead key may be readily converted to an ordinary key and that the arrangement permits more than one key being made into a silent or dead key, the parts of the dead key action being readily attached to or detached from the machine. It will be seen also that the type carrying the accent mark will not cut or puncture the paper or injure the platen and for this purpose the device 77 may be employed in connection with any key-lever to produce a bumper effect or stop and prevent injury by 90 any of the type having punctuation or other marks. 95
- From the foregoing, it will be evident that simple and efficient means is provided whereby one or more keys may be made silent to permit printing accents or under-scoring; that a simple and effective lock is provided between one or more of the keys and the parts operated thereby whereby the ribbon may be actuated without tripping the escapement; that positive means is provided whereby all liability of the key having too great a movement is avoided; that the dead key action as a whole is extremely simple; and that the dead or silent key action while 100 applicable to different kinds of writing machines is particularly adapted for machines which are adapted to fold in order that the same may be made compact to adapt the machine for transportation or like purposes. 110
- Having thus described my invention, I claim as new and desire to secure by Letters Patent:—
1. In a typewriting machine, the combination of a carriage, escapement mechanism 125

- for the carriage, key-levers, type-bars operated by the key-levers, an element for operating the escapement mechanism and operable by all of said key-levers, and means operable by one of said key-levers forming a connection between said element and the key-lever for preventing movement of said element far enough to effect movement of said escapement mechanism.
10. 2. In a visible typewriting machine, the combination of a carriage, escapement mechanism for the carriage, ribbon vibrating mechanism, key-levers, type-bars operated by the key-levers, an element for operating both the escapement and the ribbon vibrating mechanisms and operable by all of said key-levers, and means operable by one of said key-levers forming a connection between said element and the key-lever for preventing movement of said element far enough to effect movement of said escapement mechanism but effective to move the ribbon vibrating mechanism.
15. 3. In a typewriting machine, the combination of a carriage, feeding mechanism for the carriage, key-operated levers for operating the feeding mechanism, a silent key-operated lever, and an element forming a direct connection between a part of the feeding mechanism and said silent key-operated lever for making the feeding mechanism ineffective to move the carriage.
20. 4. In a typewriting machine, the combination of a carriage, feeding mechanism for the carriage, ribbon vibrating mechanism, key-operated levers for operating the feeding mechanism and the ribbon vibrating mechanism, a silent key-operated lever, and an element forming a direct connection between a part of the feeding mechanism and said silent key-operated lever for making the feeding mechanism ineffective to move the carriage and still permitting said ribbon mechanism to be operated.
25. 5. In a typewriting machine, the combination of a carriage, feeding mechanism for the carriage, key-operated levers for operating the feeding mechanism, a silent key-operated lever, and a bar forming a direct connection between a part of the feeding mechanism and said silent key-operated lever and movable by the latter for making the feeding mechanism ineffective to move the carriage.
30. 6. In a typewriting machine, the combination of a carriage, ribbon vibrating mechanism, escapement mechanism for feeding the carriage, a universal bar, key-operated levers adapted to operate the universal bar, connections between the universal bar the escapement mechanism and ribbon vibrating mechanism to move the same, a silent key-operated lever adapted to operate the universal bar, a type-bar having an accent type operated by said last-mentioned lever, and means interposed between the escapement mechanism and the silent key-operated lever to make the latter ineffective to operate said escapement to feed the carriage when the silent key is depressed.
35. 7. In a typewriting machine, the combination of a carriage, escapement mechanism for the carriage, a universal bar, key-operated levers adapted to operate the universal bar, connections between the universal bar and the escapement mechanism to move the same, a silent key-operated lever adapted to operate the universal bar, a type-bar having an accent type operated by said last-mentioned lever, and means interposed between the escapement mechanism and the silent key-operated lever to make the latter ineffective to operate said escapement to feed the carriage when the silent key is depressed.
40. 8. In a visible typewriting machine, the combination of a carriage, ribbon vibrating mechanism, feeding mechanism for the carriage, a universal bar, key-operated levers adapted to operate the universal bar, connections between the universal bar the escapement mechanism and ribbon vibrating mechanism to move the same, a silent key-operated lever adapted to operate the universal bar, a type-bar having an accent type operated by said last-mentioned lever, and a bar interposed directly between a part of the feeding mechanism and the silent key-operated lever and operated by the latter to make the silent key ineffective to operate said feeding mechanism to feed the carriage when the silent key is depressed but effective to operate the vibrating mechanism.
45. 9. In a typewriting machine, the combination of a carriage, escapement mechanism for the carriage, ribbon vibrating mechanism, key-levers, a type-bar operated by each key-lever, a rocking frame adapted to actuate both the ribbon vibrating mechanism and the escapement mechanism under the depression of some of the key-levers, and means operated by one of the key-levers to lock the rocking frame against movement far enough to actuate the escapement mechanism.
50. 10. In a typewriting machine, the combination of a carriage, an escapement mechanism for the carriage, ribbon vibrating mechanism, key-levers, type-bars operated by the key-levers, one of which carries an accent type, a rocking frame adapted to actuate both the ribbon vibrating mechanism and the escapement mechanism under the depression of some of the keys, shift mechanism for moving the carriage and frame, and a bar operated by one of the key-levers to lock the rocking frame against movement.
55. 11. In a visible writing machine in which the type-bars have an upward and rearward movement, the combination of a carriage,

- ribbon vibrating mechanism, escapement mechanism, key-levers, type-bars operated by said key-levers, a rocking frame, a universal bar, a connection between the universal bar and the rocking frame to impart movement thereto, said universal bar being adapted to be actuated by all of the key-levers, guiding means for the key-levers, and a vertically movable locking element actuated by one of the key-levers to lock the rocking frame against movement beyond a certain point to permit actuation of the ribbon vibrator but preventing actuation of the escapement mechanism.
12. In a visible writing machine in which the type-bars have an upward and rearward movement, the combination of a carriage, ribbon vibrating mechanism, escapement mechanism for the carriage, key-levers, type-bars operated by said key-levers, a rocking frame, a universal bar, connections between the universal bar and the rocking frame to impart movement thereto, said universal bar being adapted to be actuated by all of the key-levers, guiding means for the key-levers, and a vertically movable locking bar actuated by one of the key-levers to lock the rocking frame against movement beyond a certain point to permit actuation of the ribbon vibrator but preventing actuation of the escapement mechanism.
13. In a visible writing machine in which the type-bars have an upward and rearward movement, the combination of a carriage, ribbon vibrating mechanism, escapement mechanism for the carriage, key-levers, type-bars operated by said key-levers, a rocking frame, a universal bar, connections between the universal bar and the rocking frame to impart movement thereto, said universal bar being adapted to be actuated by all of the key-levers, and a locking bar forming a direct connection between a part movable with the rocking frame and movable by one of the key-levers to lock the rocking frame against movement beyond a certain point to permit actuation of the ribbon vibrator but preventing actuation of the escapement mechanism.
14. In a typewriting machine, the combination of a carriage, escapement mechanism, ribbon vibrating mechanism, a common element actuating both escapement mechanism and the ribbon vibrating mechanism, keys for actuating said element, and a vertically movable locking member actuated by one of the keys for limiting the movement of said element.
15. In a typewriting machine, the combination of a support, a carriage, escapement mechanism, a rocking element for actuating the escapement mechanism, keys for actuating said element, and a locking member actuated by one of the keys for limiting the movement of said element.
16. In a typewriting machine, the combination of a carriage, ribbon vibrating mechanism, escapement mechanism for the carriage, keys, type operated by said keys, means movable by the keys adapted to impart movement to the ribbon vibrating mechanism and trip the escapement on the depression of the ordinary keys, a silent key-operated lever, a comb plate forming a guide for said silent key-operated lever, a bracket, a locking member having a bar-like body provided with an angular end having a slot fitting over a part of said bracket and having an elongated open-ended slot at its lower end through which a part of the silent key-operated lever passes and adapted on the depression of the silent key to be moved vertically to limit the movement of the means for operating the ribbon vibrating mechanism and the escapement mechanism.
17. In a typewriting machine, the combination of a support, a carriage, ribbon vibrating mechanism, escapement mechanism for the carriage, key-levers, type-bars operated by said key-levers, means movable by the key-levers adapted to impart movement to the ribbon vibrating mechanism and trip the escapement on the depression of the ordinary key-levers, a silent key-operated lever, a bracket, a locking member having a bar-like body provided with an angular end having a slot fitting over a part of said bracket and having an elongated open-ended slot at its lower end through which a part of the silent key-operated lever passes and adapted on the depression of said key-operated lever to be moved vertically to limit the movement of the means for operating the ribbon vibrating and escapement mechanisms and making the ribbon vibrating mechanism effective and the escapement mechanism ineffective.
18. In a typewriting machine, the combination of a support, a carriage, ribbon vibrating mechanism, escapement mechanism for the carriage, a rocking frame, key-levers adapted to operate said frame, type-bars operatively connected to the key-levers, a silent key-lever also operatively connected to a type-bar and adapted to operate the rocking frame, a comb plate secured to the support and having slots adapted to receive a part of the key-levers to guide the same, a bracket secured to said support, and a vertically movable locking bar-like element guided on the bracket at one end and having a slot at the lower end thereof to fit over a part of the silent key-lever and adapted to be actuated thereby.
19. In a typewriting machine, the combination of a support, a carriage, ribbon vibrating mechanism, escapement mechanism for the carriage, a rocking frame, key-levers adapted to operate said frame, type-bars operatively connected to the key-levers, a

- silent key-lever also operatively connected to a type-bar and adapted to operate the rocking frame, a comb plate secured to the support and having slots adapted to receive a part of the key-levers to guide the same, and a vertically movable locking bar-like element guided on the support and having a slot at the lower end thereof to fit over a part of the silent key-lever and adapted to be actuated thereby to move the vibrating mechanism to place the ribbon over the printing point and to make the escapement mechanism ineffective to feed the carriage.
20. In a typewriting machine, the combination of a support, a carriage, escapement mechanism, ribbon vibrating mechanism, key-levers operatively connected to actuate the vibrating mechanism and the escapement mechanism, a silent key, and a vertically movable element operated directly by the silent key to permit the ribbon vibrator to be actuated but prevent movement of the key far enough to trip the escapement.
25. 21. In a typewriting machine, the combination of a carriage, feeding mechanism for the carriage, key-levers operatively connected to actuate the feeding mechanism, a silent key, and a movable element operated directly by the silent key to prevent move-

ment of the key far enough to make the feeding mechanism effective.

22. In a typewriting machine, the combination of a carriage, escapement mechanism, ribbon vibrating mechanism, a movable element adapted to move the vibrating mechanism and the escapement mechanism, key-levers, type-bars operated by said key-levers and adapted to move said element, and a vertically movable member adapted to form a direct lock between said movable element and one of the key-levers to limit the movement thereof.

23. In a typewriting machine, the combination of a carriage, feeding mechanism for the carriage, key-levers operatively connected to actuate the feeding mechanism, a silent key, a movable element operated directly by the silent key to prevent movement of the key far enough to make the feeding mechanism effective, and a spring normally holding said element against movement.

This specification signed and witnessed
January 21, A. D. 1915.

OTTO PETERMANN.
